W. G. HILL,
MALE URINAL DEVICE,
APPLICATION FILED DEC. 9, 1918.

1,327,042.

Patented Jan. 6, 1920.

UNITED STATES PATENT OFFICE.

WILLIAM G. HILL, OF BROOKLYN, NEW YORK.

MALE URINAL DEVICE.

1,327,042.

Specification of Letters Patent.

Patented Jan. 6, 1920.

Application filed December 9, 1918. Serial No. 265,860.

To all whom it may concern:

Be it known that I, WILLIAM G. HILL, a citizen of the United States, and residing at Brooklyn, in the county of Kings and State 5 of New York, have invented certain new and useful Improvements in Male Urinal Devices, of which the following is a specification, such as will enable those skilled in the art to which it appertains to make and 10 use the same.

This invention relates to male lavatories, waterclosets and the like and particularly to apparatus of this class designed to be used in railway stations, hotels, schools, office 15 buildings, ships and various other public places, and the object of the invention is to provide an apparatus of the class specified with improved urinal stall or stalls; a further object being to provide each stall of 20 the class specified, or the back and side walls thereof, with flushing means; and a still further object of the invention is to provide a urinal stall of the class specified which is simple in construction and opera- 25 tion as well as sanitary and efficient in use; and with these and other objects in view the invention consists in an apparatus of the class specified, constructed and operating as hereinafter described and claimed.

30 The invention is fully disclosed in the following specification, of which the accompanying drawing forms a part, in which the separate parts of my improvement are designated by suitable reference characters in 35 each of the views, and in which:—

Figure 1 is a front view of two stalls made according to my invention;

Fig. 2 a plan view of the construction as shown in Fig. 1 with part of the construction broken away and in section;

Fig. 3 a partial section on the line 3—3 of Fig. 1 on an enlarged scale, and with parts broken away;

Fig. 4 a partial section on the line 4—4 of Fig. 2 and on an enlarged scale; and

Fig. 5 a partial section on the line 5—5 of Fig. 2 and on an enlarged scale.

In the accompanying drawing I have shown in Figs. 1 and 2, two male urinal 50 stalls 10 and 11 which are mounted or placed in a suitable room or compartment, a wall of which is indicated at 12 and the floor of which is indicated at 13. The stalls 10 and 11 have a common back wall 14 which ex- 55 tends from the side wall 15 of the stall 10

to the side wall 16 of the stall 11, and the stalls 10 and 11 are formed by a central partition wall 17.

The side walls 15 and 16 and the central partition wall 17 are connected with the back 60 wall 14 adjacent to the top thereof by angular brackets as shown at 18 in Fig. 1 of the drawing. The top of the back wall 14 is beveled inwardly and downwardly as shown at 19, and the bottom of said wall 65 sets in a groove 20 in a floor slab 13^a but the front corner portion of said wall extends into a concavo-convex drain 21 in said slab 13^a as shown at 22, said drain being provided with a central discharge 23 indicated in dotted lines in Fig. 3 of the drawing. The tops of the side walls 15 and 16 are beveled inwardly and downwardly as shown at 24 in Fig. 5 of the drawing, while the top of the central partition wall 17 is 70 beveled at the opposite sides as shown at 25.

The walls 14, 15, 16 and 17 are preferably composed of slate but may be composed of any desired material, and, in practice, I secure to the upper portion of the back wall 80 14 a slab or strip 26 which extends longitudinally of the back of the wall 14, as clearly shown in Figs. 2 and 3, and between the side walls 15 and 16 and the partition wall 17 are placed other slabs or strips 27 85 which range longitudinally of the front of the back wall 14 and both of the slabs 26 and 27 are connected with the back wall 14 by bolts 28 passed therethrough and the heads of which are inclosed, or sealed by 90 cement or similar material as shown at 29. The inner faces of the slabs 26 and 27 are notched out as shown at 30 to receive a top slab or strip 31 which closes the top of a compartment 32 formed between the top of 95 the back wall 14 and the slabs 26 and 27, which compartment extends from the side wall 15 to the side wall 16.

It will be noted on consideration of Fig. 1 of the drawing that two of the bolts 28 100 are employed at the opposite sides of each of the slabs 27, and I also employ a central bolt 33 which is placed adjacent to the upper end of the slabs 26, 27 and which serves to prevent the spreading of said upper ends. Placed between the back face of the slab 27 105 and the front face of the back wall 14 are washers 34 which are mounted on the bolts 28, and which serve to form a discharge slit or aperture 35 for the compartment 32, 110

which aperture extends from the wall 15 to the wall 16.

The tops of the side walls 15 and 16 are constructed approximately in the same manner as the top of the back wall 14, or secured to the tops of said walls are outer slabs 36 and inner slabs 37, the abutting faces of which are notched at the top thereof as shown at 38 to receive top closure slabs 10 or strips 39 adapted to close compartments 40 formed between the slabs 36 and 37 at the tops of the side walls. The slabs 36 and 37 are connected with the tops of the walls 15 and 16 by bolts 41 upon which are mounted washers 42 which serve to form discharge apertures 43 for the compartments 40 between the side walls and the inner slabs 37.

Secured to the top portion of the central partition wall 17 and at the opposite sides thereof are slabs 44 and 45 which are connected with said partition wall by bolts 46. The top abutting faces of the slabs 44 and 45 are notched as shown at 47 to receive a slab or strip 48 which closes the top of a compartment 49 formed between the slabs 44 and 45 and the top of the partition wall 17. Washers 50 and 51 are mounted on the bolt 46, at the opposite sides of the partition wall 17 to form between said wall and the slabs 44 and 45 discharge apertures 52 and 53 for the compartment 49.

The partition wall 17 as well as the side walls 15 and 16 are reduced at the top thereof and adjacent to the front ends of said walls, and mounted on the front faces of the slabs 36—37 and 44—45 as well as the ends of the slabs 38 and 48 are cover plates 54 which close the front end of the compartments 40 and 49 and also form a finish for the ends of said slabs and partition wall as clearly shown in Figs. 1, 2 and 3 of the drawing. The partition wall 17 or the rear bottom corner portion thereof is cut out, or made arc-shaped in form, as shown at 55 in Fig. 3 of the drawing to permit the passage of the flush water through the concavo-convex drain 21 and out through the discharge pipe 23.

Mounted in the compartments 32, 40 and 49 are flush water supply pipes, comprising a back pipe 56 extending longitudinally of the compartment 32 and the ends of which are provided with extensions 57, which extend into the compartments 40 at the top of the side walls 15 and 16, and connected centrally of the pipe 56 is a forwardly directed pipe extension 58 which extends into the compartment 49. A supply pipe 59 is also connected centrally with the pipe 56 and passes upwardly through the slab or strip 31, as clearly shown in Figs. 2, 3 and 4 of the drawing.

The forwardly directed pipes 57 and 58 are closed by end caps 60 as indicated in Fig. 2 of the drawing, and mounted in the

pipe 56 are forwardly directed irrigation nozzles 61 through which water is discharged from the pipe 56 onto the inner face of the slabs 27, after which said water is discharged downwardly through the aperture 35 and thus down the front face of the back wall 14 of the stalls 10 and 11. The forwardly directed pipes 57 are provided with a plurality of inwardly directed irrigation nozzles 62 similar to the nozzles 61 and through which water is discharged from the pipes 57 onto the outer faces of the slabs 37, after which said water is discharged through the apertures 43 and thus down the inner faces of the side walls 15 and 16.

The pipe 58 in the compartment 49 is provided at its opposite sides with outwardly and downwardly directed irrigation nozzles 63 through which water is discharged from the pipe 58 onto the inner faces of the slabs 44 and 45 and onto the top beveled faces 25 of the partition walls 17, and said water also passes down through the apertures 52 and 53 and thus downwardly on the opposite side walls of the partition 17.

The supply of water to the pipe 59 may be constant, or said pipe may be connected with an automatic flush tank which will flush water into and through the pipes 56, 57 and 58 at predetermined intervals to keep the back and side walls of the stalls 10 and 11 constantly and intermittently flushed with water, which operation will keep the same at all times in a clean and sanitary condition.

My invention not only produces a sanitary urinal apparatus but produces an apparatus of this class which may be made at a nominal cost and set up in the desired room or compartment of a building in a minimum amount of time, and at a small expense, and while I have shown certain details of construction for carrying my invention into effect, it will be understood that various changes therein and modifications thereof may be made, within the scope of the appended claims, without departing from the spirit of my invention or sacrificing its advantages.

It will be understood that the floor or slab 13^a is composed of slate or similar material and as shown in Fig. 3, I also employ a floor spacing slab 64 which is preferably composed of slate and the inner end of which is notched as shown at 65 to receive the front end portion of the floor slab 13^a and the inner end of the slab 64 projects into the concavo-convex drain as shown at 66.

In the accompanying drawing I have shown two stalls 10 and 11 formed by a back, two side walls and a single intermediate or partition wall, but it will be understood that in practice or when more than two

stalls are required in a single room or compartment, the same are provided by increasing the length of the back wall and introducing other partition walls between the 5 end walls, as well as providing a corresponding number of pipes 58 projecting into compartments 49 at the top of each of the partition walls.

Having fully described my invention, what 10 I claim as new and desire to secure by Letters Patent, is:—

1. An apparatus of the class described, comprising a stall composed of back and side walls, slabs mounted on the front and 15 back of the top portion of the back wall to form a compartment at the top of the back wall and an aperture formed between the front slab and the back wall through which flush water discharged into said compartment may be passed downwardly 20 onto the inner face of the back wall.

2. An apparatus of the class described, comprising a stall composed of back and side walls, slabs mounted on the front and 25 back of the top portion of the back wall to form a compartment at the top of the back wall, an aperture formed between the front slab and the back wall through which flush water discharged into said compartment may be passed downwardly 30 onto the inner face of the back wall, and a slab for closing the top of said compartment.

3. An apparatus of the class described, comprising a stall composed of back and side 35 walls, slabs mounted on the front and back of the top portion of the back wall to form a compartment at the top of the back wall, an aperture formed between the front slab and the back wall, a flush water pipe mounted in said compartment, and means for discharging flush water from said pipe into said compartment and downwardly through said aperture onto the inner face of the back wall.

4. A male urinal stall apparatus of the class described formed by back and side walls and intermediate partition walls, slabs mounted at the opposite sides of each of 45 said walls adjacent to the top portion thereof to form compartments at the top of said walls, means for supplying flush water to said compartments, and an aperture formed between one of the slabs and the adjacent wall of each of said walls through which 55 flush water discharged into said compart-

ments may pass onto the inner faces of said walls.

5. An apparatus of the class described comprising a stall composed of back and side walls, the tops of which are beveled, compartments formed at the tops of said walls, flush water supply devices mounted in said compartments above the tops of said walls, and means whereby flush water may be discharged from said supply devices into said compartments and onto the inner faces of the back and side walls. 60

6. An apparatus of the class described comprising a stall composed of back and side walls, the tops of said walls being beveled, means for forming compartments at the top of said walls, flush water supply devices mounted in said compartments above said walls, means whereby flush water may be discharged from said supply devices into 70 said compartments and onto the inner faces of the back and side walls and a drain trough mounted at the bottom of the back walls and into and through which the flush water passes. 80

7. A male urinal stall apparatus of the class described formed by back and side walls and intermediate partition walls, said walls being beveled at the top, flush water supply pipes mounted above said walls, 85 means for supplying flush water to said pipes, and means whereby flush water may be discharged from said supply pipes onto the inner faces of said walls.

8. A male urinal stall apparatus of the class described formed by back and side walls and intermediate partition walls, the top of said back and side walls being beveled inwardly and the top of the partition walls being beveled laterally, flush water 95 supply pipes mounted above said walls, means for supplying flush water to said pipes, a plurality of irrigation nozzles mounted in said pipes, and means whereby flush water may be discharged from said 100 supply pipes onto the inner faces of said walls.

In testimony that I claim the foregoing as my invention I have signed my name in presence of the subscribing witnesses this 105

6th day of December, 1918.

WILLIAM G. HILL.
